UNITED STATES PATENT OFFICE

FRED CUSTER, OF TOLEDO, OHIO, ASSIGNOR TO THE DE VILBISS COMPANY, OF TOLEDO, OHIO, A CORPORATION OF OHIO

PUMP ATOMIZER

Application filed February 8, 1930. Serial No. 425,437.

This invention relates to atomizers of the character commonly used for the spraying of perfumes or other toilet liquids, and has particular reference to those generally known as the pump type of atomizer.

The object of the invention is the provision of a simple, efficient and improved atomizer of this character which is small in size to adapt it to be carried in a purse or vanity case and which may be tightly sealed against leakage of its liquid contents and have its pump locked in inoperative position by the movement of a single element. The invention is fully described in the following specification and while in its broader aspect it is capable of embodiment in numerous forms, a preferred embodiment thereof is illustrated in the accompanying drawing, in which,—

Figure 1 is a top plan view of an atomizer embodying the invention, with the parts in sealed and locked position. Fig. 2 is a central vertical section of the atomizer taken on the line 2—2 in Fig. 1. Fig. 3 is a top plan view of the atomizer with the parts in usable position. Fig. 4 is a side elevation of the atomizer with a portion in central vertical section and a part broken away and with the parts in the usable position shown in Fig. 3, and Fig. 5 is a cross section on the line 5—5 in Fig. 2.

Referring to the drawing, 1 designates the liquid receptacle of the atomizer which is small in size and preferably of cylindrical form with its top open to adapt to be closed by a spray head 2 threaded therein. This spray head has a central vertically disposed opening 3 therethrough preferably of tapered form to adapt it to receive a conical type of plug valve 4, the lower end of which has the tube 5 extending therefrom down into the receptacle 1 to near its bottom. The upper end of the tube 5 communicates with a recess 6 in the valve 4.

The spray head 2 has a spray discharge orifice 7 in one side thereof which is adapted to communicate through a passage 8 in the head and a registering passage 9 in the valve member with the socket 6 when the valve member is in the usable position shown in Fig.

4. The head 2 also has an air passage 10 extending crosswise thereof and opening at its

outer end centrally in the bottom of the discharge orifice 7 and has its other end communicating through a tube 11 with the pump member of the device, as hereinafter described. When the valve 4 is in its open position, a passage 12 therethrough registers at its ends with the separated parts of the air passage 10 and maintains such passage open, and when the valve is turned to its closed position, the passage 12 is moved out of register with the air passage 10, thus effecting a closing of such passage. Nothing new in itself is claimed for this construction of atomizer.

The air pumping means for the atomizer comprises a pump cylinder 13 in which a plunger 14 is mounted for reciprocatory movements. This plunger has a stem 15 projecting upwardly therefrom through the upper end of the cylinder to adapt the plunger to be operated in one direction by the pressure thereon of the thumb of a hand holding the device. The plunger is actuated in the opposite direction by a coiled expansion spring 16 that is mounted in the bottom of the cylinder and bears upwardly against the plunger.

The air tube 11 extends from the atomizer head 2 down between the atomizer receptacle 1 and pump cylinder 13 and enters the pump cylinder at its lower end. In the present instance the tube 11 extends down through a hollow member 17 which is disposed between the receptacle 1 and pump cylinder 13 and is recessed at its opposite sides to fit the two members 1 and 13 which are secured thereto.

The valve member 4 has an operating arm 18 projecting laterally from its upper end so as to adapt it to project over and engage the top of the plunger stem 15 when in its depressed position to retain it in such position. To facilitate such action, the arm 18 is preferably provided at its outer end with a ball member 19, which is adapted to seat in a recess 20 in the top of the plunger stem 15 when in engagement therewith, thus tending to retain the ball and stem in engagement.

The arrangement of the passages 9 and 12 in the valve 4 is such that they are turned out of register with the spray head passages 8

100

and 10, respectively, when the arm 18 is in locking engagement with the plunger stem 15, as shown in Figs. 1 and 2, and are in register with said spray head passages when the 5 valve arm is turned to the open or operative position shown in Figs. 3 and 4. The swinging movement of the valve arm 18 is limited by a pin 21 projecting from the valve at the outer end of the spray head 2 and coacting 10 with opposite end walls of a recess 22 in the spray head in which it works.

It is apparent that in the use of my improved atomizer, the operator first throws 15 the valve arm 18 to the right to release it from locking engagement with the plunger stem 15 and to throw the plug valve 4 into open relation with respect to the spray head 15 passages 8 and 10. The operator may then 20 operate the plunger to cause a discharge of air under pressure from the spray head orifice which effects a drawing up of liquid from the receptacle through the tube 5, recess 6, and 25 passages 9 and 8, as well understood in the art. When the operator is through using the atomizer, he merely depresses the plunger to the lower end of its stroke and then swings 30 the valve arm 18 to the left to effect a closing of the spray head passages and to place the ball 19 in locking engagement with the plunger stem.

I wish it understood that my invention is not limited to any specific construction, form or arrangement of the parts, as it is capable of numerous modifications and changes without departing from the spirit of the claims. 35

Having thus described my invention, what I claim as new and desire to secure by United States Letters Patent is:

1. In combination, an atomizer having a 40 head with air and liquid discharge passages, a rotary valve operable to open and close said passages, an air pump attached to the atomizer in communication with the air passage of the spray head and having a plunger with 45 an operating stem projecting without the pump cylinder, and means secured to the pump cylinder, and means secured to the valve and operable to engage the plunger stem and hold it in inoperative position when the valve is in passage-closing position.

50 2. A pump atomizer having an atomizer receptacle and a pump cylinder secured together side by side, the atomizer having a spray head with an air discharge passage in communication with the pump cylinder, a 55 plunger in the pump cylinder having an operating part projecting outwardly from the cylinder, a valve carried by the spray head and operable to open or close said air passage, and a member carried by the valve and oper- 60 able to engage said plunger part and hold the plunger in inoperative position when the valve is in passage-closing position.

3. In a pump atomizer, a liquid receptacle, a spray head in fixed relation thereto and 65 having air and liquid passages, a rotary valve

mounted in the spray head, a handle on said valve for moving the latter to open or close the spray head passages, an air pump cylinder parallel to the axis of the valve and in communication with the air passage through the 70 spray head, and a plunger operable in said cylinder, said handle and plunger being inter-engageable to lock the plunger and valve only when the valve is in closed position.

4. In a pump atomizer, a spray head having air and liquid passages therethrough, a pump having an air cylinder with an outlet conduit leading to said air passage for supplying air under pressure thereto, a rotary plug valve controlling emission from 80 said spray head, a plunger in said cylinder, and means connected to the valve and operable to engage and lock the plunger against operation when the valve is moved to closed 85 position.

5. In a pump atomizer, a spray head having air and liquid passages therethrough, a pump having an air cylinder with an outlet conduit leading to said air passage for supplying air under pressure thereto, a rotary 90 valve controlling emission from said spray head, a plunger in said cylinder, and means projecting laterally from the valve and operable to engage and lock the plunger against 95 operation when the valve is closed and to release the plunger for operation when the valve is opened.

6. In a pump atomizer, a spray head having air and liquid passages therethrough, a rotary valve mounted in the spray head and movable into positions to respectively open and close said passages, a pump cylinder having an outlet conduit leading to the air passage for supplying air under pressure thereto, a plunger in said cylinder, the axis of the cylinder being substantially parallel to the axis of the valve, and an arm projecting laterally from the valve and operable to engage and lock the plunger against operation when the valve is closed and to release 105 the plunger when the valve is opened. 110

7. In a pump atomizer, a spray head having air and liquid passages therethrough, a rotary plug valve for controlling emission from 115 said spray head, a member projecting laterally from said valve and movable therewith during opening and closing movements of the valve, and an air pump operable to supply air under pressure to said air passage and including a plunger adapted in one position to engage said valve member when the latter is closed and retain it in such position.

8. In a pump atomizer, a spray head having air and liquid passages therethrough, a rotary plug valve mounted in the spray head for controlling emission therefrom, a member projecting laterally from said valve and movable therewith during opening and closing movements of the valve, an air pump op- 125 130

erable to supply air under pressure to said air passage and including a plunger adapted, when in depressed position, to interengage with said valve member to hold the valve in closed position, and means acting on the plunger to cause it to have yielding holding engagement with said valve member.

In testimony whereof I have hereunto signed my name to this specification.
